UNITED STATES PATENT OFFICE.

HARRY F. FRENCH, OF FREMONT, OHIO, ASSIGNOR, BY MESNE ASSIGNMENTS, TO NATIONAL CARBON COMPANY, INC., A CORPORATION OF NEW YORK.

ELECTRIC BATTERY.

14,984.

Specification of Reissued Letters Patent. Reissued Nov. 16, 1920.

Original No. 1,303,286, dated May 13, 1919, Serial No. 67,530, filed December 17, 1915. Application for reissue filed February 6, 1920. Serial No. 356,706.

To all whom it may concern:

Be it known that I, HARRY F. FRENCH, a citizen of the United States, residing at Fremont, in the county of Sandusky, and State 5 of Ohio, have invented a certain new and useful Improvement in Electric Batteries, of which the following is a full, clear, and exact description.

My invention relates to electric cells in 10 which the reacting elements are kept separated until the cells are to be put into action.

Electric cells of the type above referred to can be commercially successful only to the degree to which they possess simplicity of 15 manipulation in being rendered active, promptness of electrical response to such treatment, and capability of producing service which compares favorably with that given by the ordinary cell of equal size and 20 suitable for use for similar purposes. These advantages are best attained in a cell which requires no diffusion of liquid within the cell preceding readiness for action, no addition of mix materials, and which can be readily 25 made active without the use of any tools or other instruments.

It is the object of my invention to construct electric cells that fulfil these requirements, and the details will be given in the 30 annexed specification, reference also being had to the drawings in which:—

Figure 1 is a view of the cell in the storage condition.

Fig. 2 is a perspective view of the cell in 35 its working condition.

Fig. 3 is a partial sectional view taken on the line A—A of Fig. 2.

Fig. 4 is a perspective view of the cell with certain parts removed to show its 40 construction.

Fig. 5 is an enlarged cross sectional view of the upper end of the bibulous sheathing for the zinc electrode.

Fig. 6 is a perspective view of the zinc 45 electrodes.

Fig. 7 is a perspective view of one of the depolarizing blocks used in the cell.

The invention in its broadest aspects consists in an arrangement whereby the zinc 50 electrode can be inserted in place by the user to put the cell into action. There are different ways in which this can be done, but I prefer to construct the cell with a bibulous or porous sheath in the mix which extends

up through the seal so that the zinc electrode 55 can be readily inserted therein whenever desired.

The invention is not limited to any particular shape of cell, but by way of example one of rectangular cross section has been 60 shown on the drawing.

Referring to the drawings, a plurality of carbon plates 1 are spaced apart and connected by a thin conducting strip 2 which may be soldered or otherwise fastened thereto. I prefer to form a slightly rabbeted portion 3 in the upper corner of the carbon plates which may be electroplated to readily permit of soldering the strip 2 in 65 position.

The bibulous sheath above referred to consists of two strips 4 and 5 of pulpboard or other suitable material which may be sewed or otherwise fastened together around three 70 of the edges. Before the sheath strips are sewed together the usual layer 5' of flour paste is added to one side of each strip and after drying the strips are sewed together with the flour coating on the inside. Also the upper ends are coated with paraffin or 75 some other material 6 on the inside as well as on the outside, or impregnated with the same, so that the protruding ends will not soften or deplete the cell of electrolyte by capillary action. The coatings of flour and 80 paraffin are shown in Fig. 5, the thickness of these being considerably exaggerated for 85 purposes of illustration.

After the sheaths have been made as just described they are inserted midway between 90 the carbon plates as shown partly in Fig. 4, and the usual mix consisting of carbon and manganese dioxide moistened with electrolyte solution is tamped in position around the same. When the mix is placed in the cell 95 the dry lining and paste absorb electrolyte solution therefrom to assume a moist condition in which they are conductive due to the presence of electrolyte. The moistening of the layers of dry flour on the inner surface of the sheets causes the layers of flour to combine to provide an intermediate space filled with conducting paste.

I find it most convenient to compress the mix into blocks 6' of about half the height 105 of the cell mix when fully tamped, and insert the lower tier as shown in Fig. 4, on top of an insulating layer 7 of cardboard,

pitch or other suitable material in the bottom of the container 10. I also find it advantageous to deliver a series of blows on each depolarizing block by means of a mallet and a block of wood or other suitable apparatus, which thoroughly compresses the mix in position.

When the lower layer of mix has been tamped in position the upper layer is added 10 and treated in a similar way. The mix now being all tamped in the cell, the usual layer 8 of cardboard, sand, etc., may be added, and the seal 9 poured on top to substantially the level of the container 10 which 15 may consist of suitable waterproof paper, fabric, sheet metal, or any other desired material.

The zinc electrodes consist of strips 11 and 12 and may have any form of binding 20 post desired, but in Fig. 6 I have shown the zincs 11 and 12 with bent-over lugs 13 and 14 respectively. The lug 14 carries a binding screw clamped in position by a nut 15 and a milled nut 16 threaded thereon in 25 position to clamp the conducting wire that will be attached thereto when the cell is put into use. For convenience the zinc 11 has a notch 17 in the lug 13 so that it can be readily joined to the zinc 12 and placed 30 in position by the user.

The zincs while being stored for sale or for use, can be kept in any way, but it is preferable to secure them to the outside of the cell so that they will not be lost. A 35 convenient way to do this is to place zinc 12 against the outside of the cell and with the lug 14 projecting inward. Zinc 11 can then be placed outside of the zinc 12 with the slot 17 extending around the binding 40 post 18, as shown in Fig. 1. The binding nut can then be screwed down to clamp the zinc in position, and a cord 19 tied around the cell to prevent sidewise displacement of both zincs. In this condition the 45 cell will leave the factory and be inactive until the zincs are inserted into position.

When the cell is to be put into action the user will remove them from their attached position on the outside of the cell and will 50 insert them between sheets 4 and 5 of the bibulous sheath which projects up above the seal. A zinc plate should be partially inserted in each of the sheaths protruding from the seal, and the two secured together 55 by loosening the nut 15 and springing the lug 17 beneath it where it will be rigidly clamped in position by retightening the nut on the screw. The two zincs will then be pushed as far as they will go into the 60 sheaths and the cell is ready for action.

In some cases I will keep the sheets 4 and 5 of the bibulous sheath separated by a non-active strip 4', such as a strip of paraffin paper. This will provide a cavity in 65 the sheath to render the insertion of the

zincs more convenient when the strip is pulled out.

While I have shown and described a dry cell having three carbon electrodes and two zinc electrodes, it of course will be apparent 70 that the invention could be used with only one carbon and one zinc, or with any number of such electrodes.

In the improved form of cell just described, the electrolyte, depolarizer and other 75 mix materials are thoroughly mixed and tamped in place in the cell at the factory, so that after the insertion of the zincs the cell conditions are substantially identical with those of ordinary cells found on the 80 market. The service life, voltage and current of the improved form of cell will therefore be substantially the same as in other cells, and these characteristics can be accurately controlled by the process of manufacture as they are not dependent upon the 85 user.

Having described my invention, what I claim is:—

1. In electric batteries, a container, a seal 90 in the upper end thereof and a flat electrode sheath of bibulous material, open at one end and projecting through the seal whereby the electrode can be inserted in the sheath when the battery is to be made active. 95

2. In electric batteries, an electrode, a sheath therefor consisting of two strips of bibulous material secured together at three of their edges, and a layer of flour paste on the inside surfaces of both of said sheets. 100

3. In electric batteries, an electrode sheath consisting of two strips of pulpboard secured together at their sides, a coating of sealing material on the inside surfaces near one of the ends of the sheath, and a coating 105 of flour on the remaining part of said inside surfaces.

4. In electric batteries, an electrode sheath consisting of two sheets of pulpboard sewed together on three of their edges, a coating 110 of sealing material on the inner and exterior surfaces of each sheet near one end thereof, and a coating of flour on the remaining portion of the inside surfaces of the sheets. 115

5. In electric batteries, a container, an electrolyte mixture therein, a seal above said mixture, a bibulous sheath in said mix one end extending to the exterior of the cell through said seal, and an electrode adapted 120 to be inserted in said sheath through the exterior end.

6. In electric batteries, a container, a positive electrode in the container, a bibulous sheath spaced from said positive electrode, an electrolyte and depolarizing mix packed between the sheath and said positive electrode, a seal on top of said mix, one end of said sheath extending to the exterior of the cell through said seal, and a negative 125 130

electrode adapted to be inserted therein through the exterior end.

7. In electric batteries, a container, a positive electrode therein, a bibulous sheath 5 spaced from said positive electrode, a depolarizing mix packed between the sheath and the positive electrode, a seal on top of the mix, said sheath extending above the seal, and a negative electrode adapted to be inserted in said sheath.

8. In electric batteries, a container, a plurality of carbon electrodes spaced apart and connected together by a conducting strip, an electrode sheath placed centrally in each 15 space between said electrodes, a depolarizing mix packed in the spaces between said sheaths and said carbon electrodes, a binding post connected to said conducting strip and a zinc electrode in each of said sheaths.

20 9. In electric batteries, a container, a plurality of carbon electrodes spaced apart and connected together by a conducting strip, an electrode sheath placed centrally in each space between said electrodes, a depolarizing 25 mix packed in the spaces between said sheaths and said carbon electrodes, a binding post connected to said conducting strip, a zinc electrode in each of said sheaths, overlapping projections on said zinc electrodes, 30 and a binding post secured to said projection.

10. In electric batteries, a container, a seal in the upper end thereof, and an electrode sheath of bibulous material open at one edge 35 and projecting through the seal, said sheath having a waterproof coating at the upper end.

11. In electric batteries, a container, a seal in the upper end thereof, an electrode sheath 40 of bibulous material open at one edge and projecting through the seal, and a sheet of waterproof material within the sheath.

12. In dry cells of the type described, a positive electrode, a depolarizing mix adjacent thereto, a negative electrode of sheet 45 zinc adapted to be placed in proximity to the depolarizing mix, and means adapted to establish intimate contact with the zinc, said means being located in proximity to the depolarizer and said space having an opening 50 adapted to permit the zinc electrode to be forcibly inserted therein to render the cell active.

13. In dry cells of the type described, a positive electrode, a depolarizing mix adjacent thereto, a negative electrode of sheet 55 zinc adapted to be placed in proximity to the depolarizing mix, and a pasty material adapted to establish intimate contact with 60 the sheet zinc, said pasty material being lo-

cated adjacent the depolarizing mix, and said cell having an opening adapted to permit the zinc electrode to be forcibly inserted in the pasty material to render the cell active.

14. In dry cells of the type described, a 65 positive electrode, a depolarizing mix adjacent thereto, a negative electrode of sheet zinc adapted to be placed in proximity to the depolarizing mix, a layer of bibulous material adjacent the mix, and pasty material located adjacent the bibulous material and adapted to establish intimate contact with the sheet zinc, said zinc electrode being adapted to be forcibly inserted in the paste adjacent the bibulous material 70 to render the cell active.

15. In dry cells of the type described, a positive electrode, a depolarizing mix adjacent thereto, a negative electrode of sheet 75 zinc adapted to be placed in proximity to the depolarizing mix, and an envelop of bibulous material containing paste, said envelop being located adjacent the depolarizing mix and having an opening adapted to permit the zinc electrode to be forcibly inserted 80 therein to render the cell active.

16. In dry cells of the type described, a positive electrode, a depolarizing mix adjacent thereto, a negative electrode of sheet zinc adapted to be placed in proximity to the depolarizing mix, paste adapted to establish 90 intimate contact with the sheet zinc, and means for supporting the paste in proximity to the depolarizing mix, said cell having an opening at one end adapted to permit the zinc electrode to be forcibly inserted therein to render the cell active.

17. In dry cells of the type described, an inactive element comprising a casing, a depolarizing mix, a carbon electrode and a 100 separating medium within the casing, said carbon electrode and separating medium being located on opposite surfaces of the depolarizer, and said casing having an opening adapted to permit a zinc electrode to be 105 inserted therein adjacent the separating medium and out of contact with the depolarizing mix.

18. In dry cells of the type described, an inactive element comprising a casing, a depolarizing mix, a carbon electrode and a filling of paste within the casing, said carbon electrode and paste being located on opposite surfaces of the depolarizer, and said casing having an opening adapted to 110 permit a zinc electrode to be inserted therein adjacent the paste and out of contact with the depolarizing mix.

In testimony whereof, I affix my signature.
HARRY F. FRENCH.
